UNITED STATES PATENT OFFICE

123,093

DESIGN FOR CHESSMEN

George W. Slater and Reginald Slater,
East Akron, Ohio

Application January 24, 1940, Serial No. 89,682

Term of patent 7 years

To all whom it may concern:

Be it known that we, George W. Slater and Reginald Slater, citizens of the United States of America, residing at East Akron, in the county of Summit and State of Ohio, have invented a new, original, and ornamental Design for Chessmen, of which the following is a specification, reference being had to the accompanying drawing, forming a part thereof wherein:

Figs. 1, 2, 3, 4, 5 and 6 are perspective views of the chessmen, showing our new design.

We claim:

The ornamental design for chessmen, as shown.

GEORGE W. SLATER.
REGINALD SLATER.
